UNITED STATES PATENT OFFICE

CHESTER F. JOHNSON, OF DETROIT, MICHIGAN; DETROIT AND SECURITY TRUST COMPANY EXECUTOR OF SAID CHESTER F. JOHNSON, DECEASED

ADJUSTING MECHANISM

Application filed June 12, 1929. Serial No. 370,304.

This invention relates broadly to adjusting means embodying both an initial and a limited and continued adjustment, and has special reference to the control of the fuel or air metering arrangements for carburetors of internal combustion engines.

It is an object of this invention to provide adjusting means of an improved type having a wide range of initial adjustment together with clamping means therefor which permit a limited subsequent adjustment in either direction from the initial setting, the limited adjustment being designated as a service adjustment restricted to the desired operating range predetermined by the initial or factory adjustment which compensates for normal variations in individual structures due to manufacturing tolerances and the like.

It is another object of this invention to provide an improved adjusting means of the type described incorporating two interdependent adjustment ranges.

Other and further important objects of this invention will be apparent from the disclosures in the specification and accompanying drawings.

The invention (in a preferred form) is illustrated on the drawings and hereinafter more fully described.

On the drawings:

Figure 1 is a fragmentary showing of a carburetor illustrating the application of a device embodying the features of this invention to the control of a carburetor air valve.

Figure 2 is an enlarged view of the adjusting device, with parts broken away for clearness.

Figure 3 is a fragmentary end view taken from the left of Fig. 2.

As shown on the drawings:

The carburetor features chosen to illustrate an embodiment of this invention comprise an air valve housing 10 within which is an air valve 11 shown in dotted lines, which is pivoted at 12. This valve is normally closed by a spring 13 resting on a movable support 14 which carries a button 15 on its lower end by which the support may be raised to increase the resistance to an opening movement of the air valve. The range of adjustment is

made extreme in order that the maximum spring pressure so obtained may be sufficient to maintain the valve seated against the suction within the carburetor when the engine is cranked for starting, thus insuring the delivery of an abnormal amount of fuel due to the increased suction within the carburetor when the air valve is held closed. In effect this forms a priming device analogous to the effect of the usual choke valve.

The spring support 14 and button 15 are guided by a housing 16 containing a spring 17 acting against the button 15. Associated with the housing is a bifurcated yoke 18 forming journals for a shaft 19 one end of which is bent to form a handle 20. A lever 21 is clamped by a screw 22 to the shaft 19 and has one end 23 extending through a slot in the housing to engage the button, so that when the handle 20 is moved counter clockwise, the lever end 23 lifts the button and spring support to increase the spring load acting against the air valve.

In order to limit the return movement of the lever due to the springs 13 and 17, the lever 21 is formed with an arm 24 adjacent the shank of the yoke 18, and an adjusting screw 25 extends through a threaded aperture in the arm, the end of the screw bearing against the yoke 18. This screw 25 forms the primary or initial adjustment means for the air valve opening movement and serves to vary the proportioning of fuel to air by varying the resistance opposing the opening of the air valve.

The structure so far described would form an operative combination which in skilled hands would be satisfactory, but as carburetors are often tinkered with by unskilled operators, it is desirable to limit the range of adjustment to the most desirable range. To this end a collar 26 is mounted on the screw 25 and is clamped thereto by a set screw 27 when the initial adjustment of the screw 25 has been properly set. The set screw 27 is clamped after the collar is rotated to bring the screw 27 to the top of the collar in order that it may serve as an indicator.

A clicker member 28 is also clamped by the lever screw 22, the free end 29 being notched

to engage the head end of the adjusting screw 25 in order to prevent shifting of the clicker member. The actual clicker 30 is struck from the material of the member 28 and engages in one of a series of notches 31 in the collar 26. If eight notches are provided as shown and the collar clamped with its set screw opposite the clicker member, then the adjusting screw can be shifted 1, 2 or 3 notches in either direction, a clockwise movement of the screw and collar, for a right hand screw, serving to enrich the mixture, and vice versa, the set screw 27 in either case bringing up against the clicker member to limit the range of plus or minus adjustment.

It will thus be seen that I have provided an improved and simplified adjusting mechanism incorporating a wide range of primary adjustment together with a limited range of secondary adjustment.

I am aware that numerous details of construction may be varied through a wide range without departing from the principles of this invention, and I therefore do not purpose limiting the patent granted, otherwise than necessitated by the prior art.

I claim:

1. A variable adjusting device of the class described comprising a longitudinally adjustable member, means for limiting the range of movement of said member, including movable clamping means for said member, said clamping means forming an indicator of the position of said adjustable member within the range of movement permitted by said limiting means.

2. An adjusting mechanism of the class described comprising a member having a relatively wide range of primary adjustment and clamping means therefor permitting a limited range of movement of said member.

3. In a carbureter, an air valve a spring resisting the opening of said valve, and means for varying the spring pressure comprising a lever acting to compress said spring, an adjusting screw limiting the return movement of said lever and means engaged on said screw adapted to limit the range of movement thereof.

4. In a carbureter, an air valve a spring resisting the opening of said valve, and means for varying the spring pressure comprising a lever acting to compress said spring, an adjusting screw limiting the return movement of said lever, a notched collar clamped to said screw and clicker means engaging the notches in said collar for indicating the degree of adjustment of said screw from normal.

5. In a carbureter, an air valve, a spring resisting the opening of said valve, and means for varying the spring pressure comprising a lever acting to compress said spring, an adjusting screw limiting the re-

turn movement of said lever, a notched collar mounted on said screw and clicker means for engaging the notches in said collar for indicating the degree of adjustment of said screw from normal, said clicker means cooperating with said collar to limit the range of adjustment of said screw.

In testimony whereof I have hereunto subscribed my name at Detroit, Mich., county, Wayne.

CHESTER F. JOHNSON.
